Sculptor
Franklin Simmons

DFS.2141

Franklin Simmons of Washington D.C.

Assignor to

Wm Miller of Providence, R.I.

Letters Patent No. 2141 Dated July 18, 1865.

Design for a Medallion of Vice Adm'r Farragut.

The schedule referred to in these Letters Patent and making part of the same.

To all whom it may concern:

Be it known, that I, Franklin Simmons, of the City of Washington D.C. have originated and produced a new model, of which the accompanying photograph is a true representation.

What I claim as my invention or production, and desire to secure by Letters Patent is The design for Mezzo-relief Medallion Portrait of Vice Adm'r Farragut, represented by the photograph herewith attached.

Witnesses:

Edm J. Brown
W.M. Peter Baumgras.
